UNITED STATES PATENT OFFICE.

HENRY C. HINCHCLIFF, OF BROOKLYN, NEW YORK.

PUNCHING AND SETTING MACHINE.

1,240,207.

Specification of Letters Patent. Patented Sept. 18, 1917.

Application filed January 26, 1917. Serial No. 144,620.

To all whom it may concern:

Be it known that I, HENRY C. HINCHCLIFF, a citizen of the United States, and a resident of the borough of Brooklyn, county of 5 Kings, and State of New York, have invented new and useful Improvements in Punching and Setting Machines, of which the following is a specification.

My invention relates to improvements in 10 punching and setting machines and consists in an improved construction and arrangement adapted particularly for setting rivets, lacing hooks, studs and like articles or eyelets into material or for securing 15 washers, buttons, snap fasteners or any similar article to such material.

A particularly valuable advantage attained by my present improvements consists in the adaptability of my mechanism to the 20 punching of the apertures in the material to receive the articles to be inserted, of a size corresponding to the full diameter of the articles, which is particularly desirable when inserting eyelets, rivets, and the like 25 in metal or other hard substance.

My improvements may desirably be embodied in the class of punching and eyeletting machines described in prior Patent No. 1,120,939, dated December 15, 1914, wherein 30 the punch, set and die are arranged permanently to be in axial alinement and in which an anvil is moved between the punch and set and the die.

Important features of my invention comprise means for clamping in position the material to be operated upon and means for elevating and for moving it transversely when desired while so clamped.

Other valuable features are means for 40 holding and guiding rivets, eyelets and the like into the punched hole and also into a washer or the like when it is desired to secure such articles to the material.

The described and other features of my 45 invention are illustrated in the accompanying drawings wherein like reference characters are applied to the corresponding parts in the several views.

Referring to the drawings, wherein a desirable embodiment of my invention is shown, Figure 1 is a front elevation of the parts of the machine holding the punch and set slides and of the support for the die and the anvil with the anvil retracted and a section of material clamped in place on the lift-

ing bar and the material perforated by the punch.

Fig. 2 is a right side elevation of the same.

Fig. 3 is a front elevation of the aforesaid parts of the machine partly in section with the lifting bar and the material elevated and released by the bar clamp and gripped by the feed clamp, the punch withdrawn from the material, a rivet held in place for guiding into the punched hole and the anvil moved under the material and into alinement with the set.

Fig. 4 is a left side elevation of Fig. 3.

Fig. 5 is a front elevation of the said parts of the machine with the set down, a rivet passed through the material and clenched thereto and the guiding jaws withdrawn out of the way.

Fig. 6 is a right side elevation of Fig. 5, with the lifting bar and clamp broken at the end and the material and anvil shown in section.

Figs. 7 and 8, are front and side elevations respectively of a modified arrangement 80 of jaws for guiding eyelets, rivets and the like, attached to a feed chute adapted to be moved into and out of alinement with the set and anvil.

Figs. 9 and 10 are vertical sectional views 85 taken at right angles of a modified arrangement of guide jaws adapted to guide and set lacing hooks.

Figs. 11, 12 and 13 show in section several forms of commercial closed eyelets adapted 90 to be set by my improved mechanism.

Fig. 14 is a partial view similar to Fig. 4, illustrating the feed clamp operating connections in lowered releasing position.

In Fig. 15 there is illustrated the modified 95 arrangement of the jaws "7" particularly adapted for attaching lacing hooks shown in Figs. 9 and 10, with the jaws down and a lacing hook set into the material.

The operating parts of these improvements are mounted upon a frame "1", in which is slidably mounted the set plunger "2", and the punch plunger "3", as described in my prior patent referred to. The punch and set are concentrically arranged, the punch operating through a bore in the set. The punch plunger is provided with a punch "4", and the set plunger with a set "5".

The set plunger is recessed at "6, 6" to 110

- receive the guide jaws "7, 7" which are provided with slots at "8, 8" to receive the sustaining pins "9, 9" located in the set plunger "2".
- 5 The guide jaws "7" are provided with studs "10, 10", engaging the ends of the spring "11", whose central portion rests on the end of the set plunger "2", the action of the spring "11" being to press the studs "10" 10 with the guide jaws "7" downwardly and inwardly at their lower ends.
- A stationary cam "12," mounted on the frame "1" is so shaped as to separate the guide jaws "7" by engaging the studs "10" 15 thereon when they are elevated with the set plunger "2" to receive a rivet or like article, and at its lower end is adapted to open and restrain the jaws "7" while the rivet or like article is being set into the material.
- 20 The frame "1" is provided with a die "13" adapted to coöperate with the punch "4" to perforate the material "a," and an anvil "14" is adapted to coöperate with the set "5," to set a rivet, eyelet or like through 25 the hole punched in the material.
- A clamp "15" is pivotally supported by the stud "16" on a lifting bar "17" and is operated by the extension spring "18," resting on the lug "19" of the lifting bar "17" 30 to clamp the material "a" to the lifting bar.
- An adjustable dog "20," fastened to the frame "1" by the screw "21" is adapted to open the clamp "15" from the lifting bar "17" by engaging the clamp as shown in 35 Figs. 5 and 6, when the clamp is elevated by the bar, which causes the clamp to be rocked on its pivot to opened position.
- The frame "1" is provided with a rod "22" on which slidably and pivotally operates the feed clamp frame "23."
- 40 The frame "1" is also provided with a stud "32" projecting within a portion of the feed clamp frame "23" which limits the rotatable movement of the same.
- 45 The clamp "24" is pivotally mounted on a stud "25" projecting from the clamp frame "23." An extension spring "26" is positioned between the clamp "24" and the clamp frame "23" and operates to rotate 50 the clamp "24" on the stud "25," and open the clamp "24" from the clamp frame "23."
- A lever "27," pivotally mounted on the stud "28" projecting from the clamp frame "23" is provided with a stud "29," which is 55 connected by a link "30" to a stud "31," projecting from the clamp "24" and operates to rotatably open and close the clamp "24" from the clamp frame "23."
- The lever "27" is constructed with a stud 60 rod "33" projecting therefrom into the fork of the elevating bar "34" which operates as it is elevated first to elevate the clamp frame "23" until it is stopped by the stud "32" and then to rotate the lever "27" on the stud "28" which operates to close the 65 clamp "24" to the clamp frame "23" through the stud "29," link "30" and stud "31."
- A stud "35" on the clamp frame "23" is located within the fork of the lever "36" 70 which operates to move the frame with the material, transversely as will be readily understood.
- The operation of the described mechanism in punching a hole in the material and setting a rivet, eyelet or like article therein, is 75 as follows:
- The feed clamp frame "23" being depressed with the feed clamp "24" open and the lifting bar "17" lowered. The clamp "15" 80 is opened by hand and the material to be operated upon is placed in position beneath the punch and set, and under the clamp "15," and a hole punched in the material "a" as shown in Figs. 1 and 2.
- The punch is now withdrawn from the material and elevated above the set "5," the lifting bar "17" is elevated with the material and the clamp frame "23" being lifted simultaneously, the feed clamp "24" clamps 85 the material to the clamp frame "23" as it is released by the clamp "15," engaging the dog "20." The anvil "14" is now moved beneath the material and a rivet, or eyelet placed within the guide jaws "7" by hand 90 or automatically, as shown in Figs. 3 and 4.
- The set plunger "2," set "5" and guide jaws "7, 7" with the rivet or like therein are now brought down to guide the rivet or like through the hole punched in the material and to set it thereto, as shown in Figs. 95 5 and 6, the jaws "7, 7" being opened and retarded by the studs "10, 10" thereon operating against the cam "12."
- The set plunger "2," set "5" and guide 100 jaws "7" are now elevated, the anvil "14" is returned to extreme rear position and the clamp frame "23" with the material moved transversely to the dotted position in Fig. 5, thus to feed the material preparatory to a 105 subsequent repeated operation.
- The clamp frame "23" with the material is now lowered to the dotted position in Fig. 1 and simultaneously the material is clamped by the clamp "15" to the lifting bar "17" 110 and released by the clamp "24," which now returns with the clamp frame "23" to its first position, completing the cycle of operations.
- It is obvious that where there is no need 115 of transverse movement of the material, as where one eyelet only is to be set into the material, the dog "20" can be raised out of action so that the clamp "15" and bar "17" perform all the necessary clamping functions.
- In Figs. 7 and 8, I have shown a modified 120 arrangement of the guiding jaws associated with a feed chute "39" and adapted automatically to feed the articles to the jaws 125 130

"7" and to be reciprocated by any suitable means into and out of alinement with the set at each operation of the latter to deliver the articles into position for setting, as illustrated.

The jaws are pivoted at "38" on the chute member "39" and have exerted thereon an inward pressure by means of suitable springs "40" secured on the chute member 10 "39," as will be readily understood. The articles to be attached will feed by gravity through the chute and be received by the guiding jaws "7" to be guided thereby into the hole in the material, when forced down 15 by the set "5."

In Figs. 9, 10 and 15, there is illustrated another modified arrangement of the jaws "7," particularly adapted for attaching lacing hooks. These jaws in addition to guiding 20 the article to be set, are also used to perform the function of setting a lacing hook by means of their engagement with the rim flange of the lacing hook, as shown, thus assuming this function of the set which is 25 here used principally for guiding and sustaining the punch "4."

As here shown, the jaws "7" are suitably modified to make engagement with a lacing hook and have formed thereon cam shoulders "42" to be engaged by flat springs "41." The operation thereof is as follows:—The jaws "7" are elevated in the dotted open position with the set plunger "2" until the studs "10" thereon meet the stop shoulder 30 "43," on the stationary cam "12" the further elevating of the plunger will elevate the studs "9" to a position above the shoulders "42" on the jaws whereby the springs "41" will exert a pressure thereon tending 35 to close the jaws. The jaws, however, are still held open by the cam "12" bearing against the studs "10" until the plunger is again lowered when the jaws will be forced 40 inwardly to grip a lacing hook, as shown in Fig. 9. The jaws gripping the hook, as 45 in Fig. 9, are now lowered until the lacing hook meets the anvil "14," when the plunger still descending will cause the studs "9" to move to a position as shown in Fig. 15, below 50 the jaw shoulders "42," so that the springs "41" will tend to open the jaws when the downward pressure is released. The pressure of the plunger is then imparted to 55 the lacing hook through the jaws to set the hook. Thereafter upon elevating the plunger, the pressure on the jaws being released, the springs "41" will open the jaws to release the hook and will retain the jaws open 60 until elevated into position of contact with the stop shoulders "43," which retains them in opened position as described.

An important advantage resulting from my improved arrangement and mode of operation as described, resides in the possibility of punching the hole in the material 65

as large as the outside diameter of the eyelet or rivet to be inserted.

I do not limit myself to the exact construction and arrangement of the parts of my invention shown as variations and modifications may be made without departing 70 from the spirit of the invention.

Having thus described my invention, what I claim is:

1. In a machine of the character described, 75 means for clamping in position the material to be operated upon, means for elevating the same while so clamped and means for guiding an article to be set into the material.

2. In a machine of the character described, means for clamping in position the material to be operated upon, means for elevating the same, means for guiding an article to be set into the material and means for 80 clamping and shifting the same while so clamped.

3. In a machine of the character described, the combination of a punch, a set and an anvil adapted to coöperate with the set, 90 clamping means operative to clamp the material in position during the punching operation and to elevate the material for the operation of the set and anvil and means for guiding an article to be set into the material 95 substantially as described.

4. In a machine of the character described, the combination of a punch, a set and an anvil adapted to coöperate with the set, of 100 clamping means operative to clamp the material in position during the punching operation and to elevate the material for the operation of the set and anvil, means for guiding an article to be set into the material and means adapted to clamp the material when in elevated position and to feed 105 the material for successive operations substantially as described.

5. In a machine of the character described, the combination of a punch, a set and an 110 anvil to coöperate with the set, means operative to clamp the material in position during the punching operation and to elevate the material for the operation of the set and anvil, article delivery jaws adapted to position an article to be set in the material, means acting to close the jaws, and a stationary cam engaged by the jaws and formed to open the jaws in elevated position to receive an article, and also in lowered position 115 to release the said article as it is placed in the material substantially as described.

6. In a machine of the character described, the combination of a punch, a set and an anvil adapted to coöperate with the set, 120 means operative to clamp the material in position during the punching operation and to elevate the material for the operation of the set and anvil, movable guiding jaws adapted to position an article 125

130

in the material, means adapted to open the jaws in elevated position to receive the article, and means adapted to open the jaws in lowered position to release the article 5 when placed in the material substantially as described.

7. In a machine of the character described, the combination of a punch, a set and an anvil adapted to coöperate with the 10 set, means adapted to clamp the material in position during the punching operation and to elevate the material for the operation of the set and anvil, movable guiding jaws adapted to position an article in the material, means adapted to open the jaws in elevated position to receive the article, and means adapted to open the jaws in lowered position to release the article when placed in the material and said jaws being operative 20 as a set for the article, substantially as described.

8. In a machine of the character described, the combination of a punch, a set and an anvil adapted to coöperate with the 25 set, means adapted to clamp the material in position during the punching operation and to elevate the material for the operation of the set and anvil and a second elevating and clamping means operative alternatively with 30 said first clamping means to clamp the material and adapted to advance the material to successive positions, movable guiding jaws adapted to position an article in the material, means adapted to open the jaws in elevated position to receive the article, and means adapted to open the jaws in lowered position to release the article when placed in the material substantially as described.

9. In a machine of the character described, setting jaws arranged to operate in alinement with a punch and die, said jaws being adapted to receive an article and to co-act with an anvil adapted to be moved

between said punch and die into co-acting relation with said jaws to set the said article, means for clamping in position the material to be operated upon and means for elevating the same while so clamped substantially as described. 45

10. In a punching and setting machine 50 comprising a punch, a die, and setting jaws arranged to operate in axial alinement, an anvil adapted to be moved into and out of alinement with the said punch, die, and setting jaws, means for clamping in position 55 the material to be operated upon and means for elevating the same while so clamped substantially as described.

11. In a machine of the character described, means for clamping in position 60 the material to be operated upon, means for elevating the same while so clamped and jaws adapted to receive an article and to set said article substantially as described.

12. In a punching and setting machine, 65 the combination of a punch, set and die arranged in permanent axial alinement, of means operative to clamp the material in position, means for elevating the material while so clamped and jaws adapted to receive and position an article in the material 70 to be operated upon.

13. In a punching and setting machine, the combination of a punch, set and die arranged in permanent axial alinement, of 75 means operative to clamp the material in position, means for elevating the material while so clamped and jaws adapted to receive and position an article in the material to be operated upon, and said jaws being operative to set the article, substantially 80 as described.

In witness whereof, I have signed my name to the foregoing.

HENRY C. HINCHCLIFF.
